SAND TREATING APPARATUS

Benjamin A. Smith, Cleveland, Ohio, assignor to
 The C. O. Bartlett & Snow Company, Cleve-
 land, Ohio, a corporation of Ohio

Application January 3, 1949, Serial No. 68,820

8 Claims. (Cl. 22—89)

1

The present invention relating generally as indicated to a sand treating apparatus is more particularly concerned with an apparatus and method for mixing and otherwise preparing foundry sands in a most economical manner and with a high degree of efficiency. In a still more specific sense the present invention is concerned with an apparatus and method for concurrently mixing, cooling and otherwise conditioning hot foundry sand for re-use.

As is well known, foundry sands generally comprise sand grains with predetermined quantities of bonding materials and water uniformly distributed therein for imparting the desired properties for the intended foundry purposes. Of course in pouring metal into the mold made from such sand mixtures or in treating the cores made from such mixtures, the moisture therein is driven off by the heat and likewise the bonding material also tends to burn out and lose its efficiency when exposed to the high temperatures to which ordinarily subjected whereas the sand itself is not adversely affected by such heat. Therefore, the foundry sands can be rendered re-usable by restoring the original percentages of bonding material and water and intimately blending such ingredients so as to coat the individual sand particles and thus cause them to adhere to each other and leave voids for the escape of gases. For so preparing foundry sands, various forms of mixers have been devised heretofore but each are open to the objection that the sand introduced thereinto for treatment must be relatively cool, this operation taking considerable time or else requiring additional elaborate and expensive equipment. Prior attempts to incorporate cooling means in the mixer proper have proved unsuccessful and costly to install with the result that mixers such as those which are adapted to successively knead and agitate a batch of sand therein can only accommodate pre-cooled sands.

Accordingly, it is a primary object of this invention to provide a method and apparatus which obviates the necessity of pre-cooling sand being treated.

Another object is to provide a method and apparatus for concurrently cooling and thoroughly mixing sand being treated, such cooling incidentally effecting thorough aeration of the sand and being accomplished with a minimum of additional apparatus and within a time period no longer than the usual mixing cycle.

Another object is the provision of a sand treating method and apparatus in which cooling of the sand is effected while the sand is whirled, and

2

thus thoroughly agitated, whereby a greater number of sand particles are subjected to the aforesaid influences and with a minimum quantity of coolant.

5 Still another object is the provision of a sand treating method and apparatus wherein the blowing of a coolant through the sand in the region of agitation thereof further assures a more uniform distribution of the conditioning ingredients thereof.

Other objects and advantages will appear as the description proceeds.

To the accomplishment of the foregoing and related ends, said invention, then, comprises the 15 features hereinafter fully described and particularly pointed out in the claims, the following description and the annexed drawing setting forth in detail one illustrative embodiment of the invention, this being indicative, however, of but one 20 of the various ways in which the principle of the invention may be employed.

In said annexed drawing:

Fig. 1 is a perspective view of one form of mixing apparatus;

25 Fig. 2 is a cross-section view taken substantially along the plane indicated by the line 2—2, Fig. 1;

Fig. 3 is a cross-section view taken substantially along the plane indicated by the line 3—3, Fig. 2;

Fig. 4 is a cross-section view taken substantially along the plane indicated by the line 4—4, Fig. 2; and

Fig. 5 is a cross-section view similar to Fig. 2 except illustrating a power driven agitator.

35 Referring now more particularly to the drawing, the mixing apparatus exemplarily illustrated comprises a base 1 supporting a bowl-shaped container 2 for rotation in a horizontal plane about its vertically disposed central axis, the driving means for said container comprising as for example a motor 3 supported on said base below the container and driving the latter through inter-gearing 4.

Within said container and supported on said 45 base 1 for rotation about a horizontally disposed axis are vertically adjustable kneading rolls 5 rotatably carried on a shaft 6, having its opposite ends fixed in blocks 7, and said blocks in turn being adjustable in vertical guideways formed in said base. Said rolls 5 are preferably cylindrical as shown with the peripheral faces thereof a desired distance directly above the annular horizontally disposed area of the bottom of said container and substantially co-extensive with the radial width of such area. As will hereinafter ap-

pear, the purpose of the rolls 5 is to knead and work bonding material into sand contained in said container and to break up the lumps in the sand. As evident, said rolls 5 will exert a combined squeezing and smearing action on the sand carried thereunder during rotation of said container. The clearance space between rolls 5 and container 2 may be varied as desired between zero and several inches.

Between said rolls 5 and likewise above the flat annular area of the container 2 is an agitator 8 formed with a vertically disposed tubular portion 9 and a star wheel 10 at the lower end of said portion 9. Said agitator is supported for rotation and limited vertical reciprocation on a tubular arm 11 mounted on base 1. The star wheel 10 has a bore 12 through the hub thereof and is formed with a plurality of radiating arms 13 formed with tunnels or grooves 14 on the bottom side leading from such bore 12 to the ends of the tangentially extending tips 15 on said arms, said tips and arms being of such shape as to induce rotation of the agitator in a counter-clockwise direction as viewed in Fig. 1 in response to driving of the container 2 with the batch of sand therein in the same direction. The essential purposes of the agitator 8 are to improve the mixing characteristics of the apparatus, to break up lumps in the sand and prevent caking of the sand by the kneading action of rolls 5, and to clear the sand from the bottom of the container.

As best shown in Fig. 2, the tubular arm 11 and agitator 8 define a duct or passageway 16 leading to the tips 15 of the agitator whereby a coolant (preferably air at room temperature) may be forced through said duct as from the end 17 thereof and blown through the whirlingly agitated sand particles surrounding the agitator. Such blowing of coolant through the whirling sand not only effects a desired reduction in temperature of the hot sand which may be loaded into the apparatus by driving off any excess moisture but additionally aerates the sand to render the same fluffy and easy to ram into a mold, facilitates breaking up of the sand, and further tends to impel the agitator 8 in the same direction as caused by the movement of sand therewith whereby to still more effectively agitate and thus more thoroughly mix the sand.

On the other side of the container 2 is a scraper disk 18 which is mounted on said base 1 for free rotation about its central horizontally disposed axis and for swinging movement about a vertical axis from a position with its leading edge engaging the rim of the container and inwardly facing surface deflecting the sand being treated inwardly for kneading by the rolls 5 to a position with its leading edge spaced from the rim of the container whereby said rim and the other surface of the disk define a channel for collecting the thoroughly mixed and cooled sand and causing such sand to overflow the rim for discharge through any suitable chute into a receptacle disposed below said container.

It can now be seen that with hot sand and other necessary ingredients charged into container 2 to restore the respective percentages of the latter to a desired amount and thus condition the sand for subsequent use and with the container 2 driven counter-clockwise as shown, the rolls 5 will knead or squeeze the sand passing thereunder and the rotating agitator 8 will impart a rotary whirling action in the sand. At the same time room temperature air caused to flow under pressure through the passageway 16

will be blown through such whirling sand whereby to effectively reduce the temperature thereof and otherwise influence the sand in the particulars already described. Thus, the air issuing from the tunnels 14 will cool the sand to a desired temperature and at the same time aerate the same and facilitate thorough agitation thereof. The coolant which, as indicated, may be room temperature air, is preferably forced through the passageway 16 by a turbine blower or pressure fan at a pressure less than 1 p. s. i., viz. about $\frac{1}{2}$ p. s. i.

To further facilitate thorough mixing and aeration of the sand being treated, the agitator 15 may be power driven as shown in Fig. 5, said agitator and drive therefor comprising a star wheel 10, preferably the same as that previously described; a tubular portion 18 provided with lateral ports 19 adjacent its upper end and connected at its lower end to said star wheel 10, and a conduit 20 supporting said agitator for rotation about a vertically disposed axis and forming therewith an annular chamber 21 through which air or other coolant may flow to the ports 19 and thence through the tubular portion 18, and tunnels 14 in said star wheel during rotation of said agitator. Power driving of said agitator as herein exemplarily illustrated is effected by an electric motor 22 mounted on conduit 20 and meshing bevel gears 23 and 24 respectively keyed to the drive shaft of said motor and to the upper end of the agitator. Said gears are enclosed within a housing 25 and thus protected from damage by the sand.

As apparent, when coolant is forced through the conduit 20 and through the agitator and while the motor 22 is energized, the apparatus as a whole will function in the manner indicated above except that because of the power driving of the agitator at a desired speed independent of the speed of rotation of the container 2, a more thorough mixing and aeration of the sand is made possible.

Other modes of applying the principle of the invention may be employed, change being made as regards the details described, provided the features stated in any of the following claims, or the equivalent of such, be employed.

I therefore particularly point out and distinctly claim as my invention:

1. In a sand treating apparatus, the combination of a rotary container for sand to be treated, a roll exerting pressure on the sand in said container, and a rotary agitator in said container circumferentially spaced from said roll and adapted to be buried in the sand, means supporting said agitator for rotation in the sand moving therewith to thus impart a rotary agitating motion to the sand, said agitator being provided with a coolant supply passage therein terminating near the bottom of the container so that air is discharged adjacent the bottom of the container for aerating the sand.

2. The method of treating sand comprising successively kneading and inducing a whirling agitating action in the kneaded sand, and during the agitation blowing a coolant through the sand from a point below the surface thereof and in the region of the whirling agitating action.

3. In a sand treating apparatus, the combination of a horizontally disposed bowl-shaped container for sand to be treated, a base supporting said container for rotation about its central vertical axis, means for rotating said container 70 and the sand therein, a pair of circumferentially

spaced kneading rolls having their central axes disposed in a horizontal plane and extending generally radially of said container and having their peripheral faces spaced a desired distance above the bottom of said container whereby to exert pressure on the sand in said container, means supporting said rolls for rotation about their central axes whereupon movement of the sand under said rolls during rotation of said container causes rotation of said rolls and consequent kneading and squeezing of the sand, an agitator in said container disposed between said rollers and adapted to be buried in the sand in said container, and means supporting said agitator for rotation about a vertically disposed axis, said agitator being provided with agitating elements in the sand operative to rotate said agitator responsive to movement of the sand therewith during rotation of said container and thus agitate the sand, said agitator further being provided with an air supply duct terminating near the bottom of the container so that air is discharged adjacent the bottom of the container.

4. In a sand treating apparatus, the combination of a horizontally disposed bowl-shaped container for sand to be treated, a base supporting said container for rotation about its central vertical axis, means for rotating said container and the sand therein, a pair of circumferentially spaced kneading rolls having their central axes disposed in a horizontal plane and extending generally radially of said container and having their peripheral faces spaced a desired distance above the bottom of said container whereby to exert pressure on the sand in said container, means supporting said rolls for rotation about their central axes whereupon movement of the sand under said rolls during rotation of said container causes rotation of said rolls and consequent kneading and squeezing of the sand, an agitator in said container disposed between said rollers and adapted to be buried in the sand in said container, and means supporting said agitator for rotation about a vertically disposed axis, said agitator being provided with a plurality of radially extending arms buried in the sand and closely adjacent the bottom of said container operative to rotate said agitator responsive to movement of the sand therewith during rotation of said container and thus agitate the sand and free the sand squeezed against the bottom of said container by said rolls, said agitator further being provided with an air supply duct leading to the arms of said agitator and discharging adjacent the bottom of the said container for aerating the sand.

5. In a sand treating apparatus, the combination of a horizontally disposed bowl-shaped container for sand to be treated, a base supporting said container for rotation about its central vertical axis, means for rotating said container and the sand therein, a pair of circumferentially spaced kneading rolls having their central axes disposed in a horizontal plane and extending generally radially of said container and having their peripheral faces spaced a desired distance above the bottom of said container whereby to exert pressure on the sand in said container, means supporting said rolls for rotation about their central axes whereupon movement of the sand under said rolls during rotation of said container causes rotation of said rolls and consequent kneading and squeezing of the sand, an agitator in said container disposed between said

rollers and adapted to be buried in the sand in said container, and means supporting said agitator for rotation about a vertically disposed axis, said agitator being provided with a plurality of radially extending arms buried in the sand and closely adjacent the bottom of said container operative to rotate said agitator responsive to movement of the sand therewith during rotation of said container and thus agitate the sand and free the sand squeezed against the bottom of said container by said rolls, said agitator further being provided with an air supply duct leading to the outer ends of the arms of said agitator for aerating the sand during agitation thereof.

6. In a sand treating apparatus, the combination of a horizontally disposed bowl-shaped container for sand to be treated, a base supporting said container for rotation about its central vertical axis, means for rotating said container and the sand therein, a pair of circumferentially spaced kneading rolls having their central axes disposed in a horizontal plane and extending generally radially of said container and having their peripheral faces spaced a desired distance above the bottom of said container whereby to exert pressure on the sand in said container, means supporting said rolls for rotation about their central axes whereupon movement of the sand under said rolls during rotation of said container causes rotation of said rolls and consequent kneading and squeezing of the sand, an agitator in said container disposed between said rollers and adapted to be buried in the sand in said container, and means supporting said agitator for rotation about a vertically disposed axis, said agitator being provided with a plurality of radially extending arms buried in the sand and closely adjacent the bottom of said container operative to rotate said agitator responsive to movement of the sand therewith during rotation of said container and thus agitate the sand and free the sand squeezed against the bottom of said container by said rolls, said agitator further being provided with an air supply duct leading to the outer ends of the arms of said agitator for aerating the sand during agitation thereof, the under side of said arms being formed with radially extending channels leading to the outer ends of said arms.

7. In a sand treating apparatus, the combination of a horizontally disposed bowl-shaped container for sand to be treated, a base supporting said container for rotation about its central vertical axis, means for rotating said container and the sand therein, a pair of circumferentially spaced kneading rolls having their central axes disposed in a horizontal plane and extending generally radially of said container and having their peripheral faces spaced a desired distance above the bottom of said container whereby to exert pressure on the sand in said container, means supporting said rolls for rotation about their central axes whereupon movement of the sand under said rolls during rotation of said container causes rotation of said rolls and consequent kneading and squeezing of the sand, an agitator in said container disposed between said rollers and adapted to be buried in the sand in said container, and means supporting said agitator for rotation about a vertically disposed axis, said agitator being provided with a plurality of radially extending arms buried in the sand and closely adjacent the bottom of said container operative to rotate said agitator re-

sponsive to movement of the sand therepast during rotation of said container and thus agitate the sand and free the sand squeezed against the bottom of said container by said rolls, said agitator further being provided with an air supply duct leading to the outer ends of the arms of said agitator for aerating the sand during agitation thereof, the under side of said arms being formed with radially extending channels leading to the outer ends of said arms, said channels terminating in lateral openings in said arms so disposed that air discharged through such openings tends to rotate said agitator in the same direction as rotated by the sand.

8. The structure defined in claim 1 including power means for rotating said agitator.
